SHADE BRACKET

Samuel Benjinson, New York, N. Y., assignor to
Sarah Benson, New York, N. Y.

Application December 14, 1932, Serial No. 647,134

8 Claims. (Cl. 156—24)

This invention relates to window sash brackets for shades and particularly to that class adapted to be mounted on the upper sashes of windows so as to travel therewith when subjected to sliding operations.

A principal object of the invention is to provide shade brackets adapted to be mounted on the upper sliding sash of a window so that a shade mounted thereon will be protected by the window pane against breezes blowing through the window opening.

Another principal object is to insure the full ventilation of a room in accordance with the degree of window opening, without obstruction to such ventilation by the window shades.

Another principal object of the invention is to adapt the bracket arms to be readily removed from the window sash, in order to clean the window or for other desirable purposes.

Another principal object of the invention is to make the bracket arms of such length as to support the shades in a vertical plane beyond that of the lower sash.

Another principal object of the invention is to provide a bearing on the fixture adapted to be engaged by the lower sash to raise the upper one therewith.

Other objects will be apparent from reading this specification, taken in connection with the accompanying drawings, in which

Figures 1 and 2 show respectively a top view and an end view of a form of bracket embodying my invention;

Figures 3 and 4 are similar views respectively of another form of bracket embodying my invention;

Figures 5 and 6 are similar views of still another embodiment of my invention;

Figure 7 is a top view of another form embodying my invention, in which a bearing flange adapted to be engaged by the lower sash is shown;

Figure 8 is a cross section taken along the line 13—13 of Figure 7;

Figure 9 is a face view of an additional form of bracket arm and attaching member embodying my invention;

Figure 10 is a top view of the form shown in Figure 9 taken along the line 15—15 of said figure;

Figure 11 is a face view of the attaching member associated with the embodiment shown in Figure 9;

Figure 12 is a perspective view of a detachable hinge pin used in my construction;

Figure 13 is a perspective view of another form embodying my invention;

Figure 14 is a similar view of the bracket arm for the form shown in Figure 13; and

Figure 15 is a cross section taken along the line 20—20 of Figure 13, looking in the direction of the arrows.

Referring now in detail to the drawings in which similar characters refer to similar parts throughout, an embodiment of my invention is shown in Figures 1 and 2. Here the bracket arm is shown at 46 and is in angular form, the portion 47 being shown at an acute angle to the attaching member 48. In this form the stop 49 is punched upwardly from the portion 47 of the bracket arm, but not detached from said bracket arm portion. This stop cooperates with the face of the attaching member 48 to maintain the bracket arm in its preferred servicing position. An additional stop 50 is shown in this figure where the bracket portion 47 meets the corner of the attaching member 48.

Figures 3 and 4 show another form of embodiment of my invention which is similar to that shown in Figures 1 and 2, except for the omission of the punched up stop shown in said figures. The stop in the form now being described is effected by the bracket arm portion 51 coming in contact with the corner of the attaching member 52.

Figures 5 and 6 also embody the invention. In this form a stop is effected by the bracket arm portion 53 cooperating with the face of the attaching member 54 as shown.

In Figures 7 and 8 another embodiment of my invention is shown in which the bracket arm 36 is in angular form, and is provided with a flange 37 adapted to lie in the path of travel of the lower sash 23, for the purpose of providing a bearing surface for the lower sash when it is intended to raise both sashes at the same time, in which case the lower sash only is manipulated. This flange, while shown only in these Figures 7 and 8, may, of course, be used in all embodiments of the present invention. In the form now being described, the bracket arm is bent at 38, forming a stop against the attaching fixture 39, which stop restricts the outward swing of said bracket arm, thereby providing means to locate it in its best servicing position.

In Figures 9, 10 and 11 another embodiment of my invention is shown. In this form the attaching member is provided with an abnormally deep recess 41 in its hinge side to enable the open hinge member 42, in the form of a tongue at the

100

105

110

hinge end of the bracket arm portion 44, to be inserted under the pin 43 without necessarily moving the pin from the hinge assembly. The face of the attaching fixture 40 in cooperation with the slanting portion 44 of the bracket arm 45 constitutes the stop for this form of hinge so as to locate the bracket in its preferred servicing position.

In Figures 12, 13 and 14 of the drawings another form of embodiment of the invention is shown. Here, the bracket arm 55 is angular in form, the smaller side being indicated at 56. On the latter side is provided a fastening element 57 adapted to engage frictionally with the attaching member 58 through the slot 59. A corresponding fastening element, although not shown, may be provided at the lower side of this form. The stop in this form of my bracket assembly is caused by contact of the smaller side 56 of the bracket arm with the face of the attaching fixture 58.

In all of the embodiments shown, I prefer to use a detachable hinge pin, except as to the embodiment shown in Figures 9, 10 and 11 in connection with which I have no preference as to the style of pin to be used.

In operation a pair of attaching fixtures are secured in any well known manner to the upper rail or the upper pair of stiles of an upper sash, one of such attaching fixtures being secured at each side of the sash. A bracket arm is then hinged into each of the attaching fixtures by dove-tailing or aligning the hinge elements of the attaching fixtures with the hinge elements of the bracket arms and inserting hinge pins to connect said hinge elements in operative position. Of course where the commercial form of bracket includes a hinge pin already in place, the attaching element may be secured to the sash in the same manner as in the form where the hinge pins are detachable.

A shade roller may then be mounted between the bracket arms and supported in the roller carrier elements provided therefor, in the usual manner. The bracket arms extending across the vertical plane of the lower sash and beyond such plane, the shade will hang away from both the upper and lower sash obviating the possibility of creasing the shade by contact therewith. Upon lowering and raising the upper sash it will be seen that the shade will travel therewith and at all times be shielded from the ravages of breezes blowing through the open part of the window structure. Also, it will be seen that full ventilation will result for the room equipped with my shade brackets in accordance with the size of the window openings. Furthermore, a proper circulation of air is assured by reason of the uninterrupted open passage at the top of the window when the upper sash is lowered.

In case it is desired to clean the windows or paint the woodwork the shade rollers may be readily removed from their brackets. The bracket arms may also be as readily removed from their hinges by removing the hinge pins.

The brackets may be used as bearings for the lower sash when the lower sash is manipulated to raise the upper sash, by raising the lower sash so that the top of the lower sash will engage said brackets and force them upward with their connected upper sash. This is very desirable where no window pole or other means available is convenient for closing the upper sash. The flange

illustrated in Figure 7 may also be desirable as a bearing surface for this purpose, thus obviating the possibility of marring the lower sash where it would otherwise contact with the comparatively narrow edge of the bracket arm.

I have illustrated and described what I believe to be the best embodiments of my invention. I do not wish to be limited in patent protection, however, to the embodiments shown but what I desire to secure by Letters Patent is set forth in the appended claims.

1. In a shade bracket, an attaching fixture, a bracket arm, hinge elements on said attaching fixture and bracket arm adapted to cooperate with each other, a removable hinge pin adapted to hold said attaching fixture and bracket arm in hinged relationship, and a stop extending from said bracket arm adapted to limit the swinging of said bracket arm in one direction, said bracket arm being adapted to swing to the vertical plane of its support in the other direction.

2. In a shade bracket, an attaching fixture and a bracket arm hinged together and a stop extending from said bracket arm adapted to limit the swing of said bracket arm in one direction, said bracket arm being adapted to swing to the plane of its support in the other direction.

3. In a shade bracket, an attaching fixture and a bracket arm hinged together and a stop adapted to limit the swing of said bracket arm in one direction, said bracket arm being adapted to swing to a plane parallel to its support in the other direction, a bearing means on said bracket arm adapted to be engaged by the lower sash of a window to raise the upper sash.

4. In combination with a window frame having upper and lower sliding sashes, a pair of shade brackets each embodying a bracket arm and an attaching fixture hinged together, said shade bracket being adapted to be secured to the upper sash, and said bracket arms being of such length as to extend through the vertical plane of the lower sash, and stops extending from said bracket arms adapted to limit the swing of said respective bracket arms in one direction, said bracket arms being adapted to swing to the plane of the respective attaching fixtures in the other direction.

5. In a shade bracket, an attaching fixture and a bracket arm hinged together, a stop extending from said bracket arm adapted to limit the swing of said bracket arm when in extended position, and means for holding the bracket arm in such position.

6. In a shade bracket, an attaching fixture and a bracket arm hinged together, a stop extending from said bracket arm adapted to limit the swing of said bracket arm in one direction, said bracket arm being adapted to swing to a plane parallel to its support in the other direction and rest against the sash on which it is mounted.

7. In a shade bracket, an attaching fixture and a bracket arm hinged together, and a fastener extending from the bracket arm adapted to engage with the attaching fixture to hold the bracket arm in outwardly extended position.

8. A shade-supporting bracket comprising two hinged members, one of said members having a recess in its surface, and a flange on the other member adapted to engage a wall of said recess to hold the members in approximately parallel positions.

SAMUEL BENJINSON.
